UNITED STATES PATENT OFFICE.

HANS E. THEISEN, OF MUNICH, GERMANY.

DISINTEGRATOR-LIKE DEVICE FOR PURIFYING, COOLING, AND MIXING GASES.

1,187,940.

Specification of Letters Patent. Patented June 20, 1916.

Application filed July 13, 1915. Serial No. 39,706.

To all whom it may concern:

Be it known that I, HANS EDUARD THEISEN, a citizen of the United States of America, residing at Elisabethstrasse 34, Munich, Bavaria, in the Empire of Germany, have invented a new and useful Disintegrator-Like Device for Purifying, Cooling, and Mixing Gases, of which the following is a specification.

The present invention relates to a disintegrator-like device for purifying, cooling and mixing gases and consists in forming the stationary and rotating or oppositely moving disintegrator-surfaces like the guiding- and traveling blades of turbines, and arranging the same at such an angle in relation to each other that the gas- and water-mixture may be passed practically free of shocks from the traveling disintegrator-surfaces to those which are either stationary or moving in an opposite direction.

In order to render the present invention more easily intelligible reference is had to the accompanying drawings.

Figure 1 illustrates the known form of embodiment, having radially arranged disintegrator-surfaces, while Fig. 2 shows a form of embodiment according to the present invention, in which the turbine like disintegrator-surfaces are shown diagrammatically in cross section. Figs. 3 to 9 illustrate various modifications of turbine-disintegrators.

In the form of embodiment shown in Fig. 1, the gas- and water-mixture is forced, as may, for instance, be seen from the diagram, against stationary baffle-plates at an angle α , this angle resulting from the outlet-speed a and circumferential speed b . As a result the gas- and water-mixture leaves the traveling disintegrator-plates or blades, and enters the stationary blades or disintegrator-surfaces with a relatively great loss of power, caused by the shocks.

From the diagram shown in Fig. 2 it may be seen that with a slanting or turbine-like arrangement of the blades, at a relative outlet-speed a of the gas- and water-mixture from the traveling disintegrator blades p , and a circumferential speed b of the latter, the stationary disintegrator-blades r are arranged at an angle, which results from the resulting force of a and b . Consequently in this case the mixture is passed well free of shocks, so that losses are prevented and power is saved. When choosing such an

embodiment of a disintegrator-like device for washing, purifying and cooling gases, the gas and water-mixture is always guided along the traveling and stationary disintegrator blades and, therefore, owing to the shock-free passage each turbine-blade acts, so to say, in itself as a small washing-surface. Now, as any loss of power due to shocks is obviated and the gas- and water-mixture passes from one blade to the other theoretically free of shocks the washing-, cooling- or mixing actions are performed with a minimum of power expenditure.

For the outlet-speed of the gas- and water mixture the component force, generated by the revolving disintegrator-blades is to be considered, to which, in such gas washers, combined with a ventilator, the component force generated by the ventilator, must be added, provided the gas and the water pass through the disintegrator and ventilator in the same direction; or the component force must be subtracted, provided the gas passes through the disintegrator in a direction opposite to that of the washing water.

According to the modification shown in Fig. 3 the turbine-disintegrator is arranged within a ventilator v , in such a manner that the gas- and water mixture passes through the turbine disintegrator in the same direction.

The modification according to Fig. 4 shows the disintegrator arranged laterally of the ventilator v and the water is thrown in at m in such a manner that a part of the water flows through the disintegrator from inside to outside in the direction of the arrow 1, i. e. in a direction opposite to that of the gas sucked in from outside to inside in the direction of the arrow 2.

Fig. 5, on the left hand side, is a section on the line A—B of Fig. 3, and on the right hand side a section on the line A—B of Fig. 4 and shows details of a form of embodying the turbine-disintegrator surfaces.

In Fig. 6 a modification of the turbine-disintegrator is shown, through which the gas is sucked from inside to outside or vice versa, through a separately arranged ventilator, as is diagrammatically shown, for instance, in Fig. 7. The water is introduced through a pipe n .

Fig. 8 illustrates another embodiment, in which the turbine-disintegrator-blades are driven in opposite directions by means of two pulleys p, q . The gas may enter at r

in the direction of the arrows and escape at *s* the water being previously injected in or otherwise introduced from the outside of the disintegrator. It is self-evident that in a 5 reversed direction the gas may be introduced at *s* and sucked off at *r*. In this case the water may be introduced, for instance, through the hollow shaft in a known manner.

10 Fig. 9 shows still another modification of a turbine disintegrator according to which on the outside, and around the same, additional ventilator blades *t* and, laterally of the same, a ventilator *u* are arranged 15 in such a manner, that the gas passes through the purifier in the direction of the arrows, so that the greatest part of the impurities carried along, especially tar, are deposited upon the slanting washing surface *w* and led off through a gutter *x*.

The modification just described is especially useful in connection with small gas purifiers.

20 The turbine disintegrator blades may be 25 made in any desired manner; so, for instance, the traveling disintegrator surfaces may be made of angle-irons, the radially outwardly extending legs, of which (Fig. 2) may be bent and curved like a turbine 30 blade. Also slantingly positioned flat iron pieces may be used as traveling disintegrator surfaces, as is shown in Fig. 5 by way of example.

35 It is also advantageous, in connection with the present invention, to cast the disintegrator- or turbine-blades into single disks *G'*, *G* (Figs. 3 and 4) or attach them to the

same and to arrange the disks *G* in the ventilator casing in such a manner, that, in case the ventilator casing consists of two 40 parts, the ventilator-wheel and the disintegrator may be lifted from the same, without necessitating the casing portions to be moved laterally one from another.

As may be seen from Fig. 3 the outer 45 parts of the disks *G'* *G* may be broader and stronger than their inner parts so that the diameter of the disintegrator otherwise increasing gradually toward the outside, may be decreased according to need.

50 It may also be noted that the ventilator may entirely be dispensed with in cases where the gas to be purified is fed to the disintegrator with sufficient pressure.

I claim as my invention:— 55

1. In a machine for the purpose set forth, a casing, and sets of opposed baffles therein, the baffles of one set being inclined relatively to the baffles of an adjacent set whereby a mixture of gas and water may pass 60 without appreciable shock from one set of baffles to another.

2. In a machine for the purpose set forth, a casing and a plurality of sets of baffles therein, the baffles of one set being inclined 65 in one direction and the baffles of another set being inclined in an opposite direction.

In testimony whereof I affix my signature in the presence of two witnesses.

H. E. THEISEN.
